UNITED STATES PATENT OFFICE.

CLAUDE L. HAGEN, OF NEW YORK, N. Y.

DESIGN FOR A STAGE-SCREW.

42,602.

Specification for Design.

Patented June 11, 1912.

Application filed November 15, 1911. Serial No. 660,534. Term of patent 7 years.

To all whom it may concern:

Be it known that I, CLAUDE L. HAGEN, a citizen of the United States, residing in the city, county, and State of New York, have invented a new, original, and ornamental Design for a Stage-Screw, of which the following is a specification, reference being had to the accompanying drawing, forming a part thereof.

The figures of the drawing are elevations of a stage screw showing my new design.

Figure 1 is a front elevation and Fig. 2 is a side elevation.

I claim:

The ornamental design for a stage screw as shown.

CLAUDE L. HAGEN.

Witnesses:

CLARA B. PRICE,
ANNIE HAGEN.
